DATA TRANSMISSION SYSTEM

Douglas E. Morrison, United States Army,
Trenton, Ga.

Application April 9, 1941, Serial No. 387,658

3 Claims. (CL 33—48)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a data transmission system especially adapted for use in an ordnance fire control organization.

It is a prime object of the invention to provide a flexible and simple data transmission system that can be controlled by one or more operators located at spaced points.

A further object of the invention is to provide a data transmission system adapted to the deliberate and controlled dispersion of gunfire.

A still further object of the invention is to provide a fire control system adapted for the purpose of causing the guns controlled thereby to systematically search the area in the vicinity of the predicted position of the target.

The specific nature of the invention as well as other objects and advantages thereof will clearly appear from a description of a preferred embodiment as shown in the accompanying drawings in which:

Fig. 1 is a plan view of the data transmission system of this invention;

Fig. 2 is a longitudinal sectional view through the junction box taken upon the line 2—2 of Fig. 1;

Fig. 3 is an end elevation of the junction box as viewed from the right end of the junction box as seen in Fig. 1;

Fig. 4 is a transverse sectional view through the junction box taken upon the line 4—4 of Fig. 2;

Fig. 5 is a longitudinal sectional view through one of the transmitters, all of which are substantially identical in construction; and

Fig. 6 is a longitudinal sectional view through one of the receivers, all of which are substantially identical in construction.

Referring now to the drawings and more particularly to Fig. 1, there is shown a data transmission system in accordance with the present invention which comprises a junction box 10, superelevation transmitter 11, vertical deflection transmitter 12, arbitrary vertical deflection correction transmitter 13, flexible hydraulic transmission conduit 14 connecting the transmitters 11, 12, 13 with the junction box, lateral deflection transmitter 15, arbitrary lateral deflection correction transmitter 16, flexible hydraulic transmission conduit 17 connecting the transmitters 15, 16 with the junction box, a vertical and lateral deflection receiver 18 and 19, respectively, for each gun G, and hydraulic transmis-

sion conduits 20, 21 connecting the vertical and lateral deflection receivers of each gun G with the corresponding outputs of the junction box, respectively.

5 Each of the transmitters 11, 12, 13, 15 and 16 are substantially identical in construction aside from the fact that the graduated scales thereof will be varied to conform with the deflections to be transmitted, consequently a description of one will suffice as a disclosure for each of the transmitters which with reference to Fig. 5 will be seen to comprise a cylinder 22 formed at one end portion to receive in fluid-sealed relation a tubular outlet member 23. At its opposed end portion, the cylinder 22 is internally threaded or otherwise suitably formed in similar manner to receive a screw 24 which may be rotated in interthreaded relation with respect to the cylinder to advance its inner end portion 25 from substantially the rear end of the bore of the cylinder to the front end thereof and vice versa. To prevent fluid in the bore of cylinder 22 from bypassing the interthreaded connection between the cylinder and screw 24, an obturator cup 26 of rubber or similar flexible material is attached to the inner end portion 25 of the screw in snug-fitting relation to the bore of the cylinder, as by the removable fastener 27 as indicated in Fig. 5. A handwheel 28 is keyed or similarly affixed upon 15 the outer end portion of the screw 24 to facilitate manual rotation thereof and a graduated scale S is secured to the cylinder 22 longitudinally thereof graduated in units of the particular deflection or other value to be transmitted which 20 in the case of transmitter 11 would be superelevation. A pointer 29 is slidably mounted upon the cylinder for movement of its index end over the scale S and is biased by a spring 30 into a normal position wherein its outer end 31 engages 25 the handwheel 28 whereby translatory movement of the handwheel in advancing the screw 24 will move the pointer inwardly over the scale and the spring 30 will act to move the pointer outwardly over the scale as the handwheel 28 30 is translated reversely in retracting the screw.

The junction box 10 comprises a rectangular frame 32 supported by legs 33 at its four corners. Suitable members 34 provided with longitudinal ways 35 are secured to the longitudinal sides of frame 10 with the ways in planar relation. In one end portion of the frame 10 a rectangular vertical deflection cylinder block 36 is disposed for sliding movement within the frame as by having tongues 37 formed on its opposed sides disposed in the ways or grooves 35 of mem-

bers 34. A similar cylinder block 38 is similarly disposed in the opposed end portion of frame 10 for lateral deflections. Each of the cylinder blocks 36 and 38 comprises a plurality of through parallel cylindrical bores 39, one bore for each of the guns with which the system is to be employed, conveniently shown as four in the present disclosure for the purpose of illustration. The outer ends of the bores 39 of each of the cylinder blocks 36, 38 are closed in fluid-sealed relation by plugs 40 adjustable by means of adjusting screws 41 mounted in interthreaded relation in blocks 42 secured in the outer end portion of each bore 39. A piston 43 is mounted in each of the bores 39 of each cylinder block 36, 38 and piston rods 44 are secured to each of the pistons in opposed axial alignment as shown in Fig. 1. A cam 45 is mounted between the opposed ends of the piston rods 44 for sliding movement transversely of the frame 10 and is maintained in a normal predetermined position by springs 46 interposed between the outer sides of the members 34 and the adjacent ends of the cam outwardly projecting through the members. To facilitate transverse sliding movement of the cam 45, a lever 47 is pivoted at its lower end portion 48 to a member 49 suitably secured transversely of the frame 10, and inserted through an aperture 50 in the cam 45 to project a distance above the cam convenient for manipulation by an operator whereby pivotal movement of the lever will slide the cam transversely of the frame 10. To slide the cylinder blocks 36, 38, a cylinder 51 is rigidly secured to either opposed end of the frame 10 and formed at its outer end to receive in fluid-sealed relation the flexible hydraulic conduit 14 or 17, as the case may be. Pistons similar to pistons 43 are mounted in the cylinders 51 and attached by means of the piston rods 52 to the cylinder blocks. The bores 39 are formed with outlets 53 adapted to be connected in fluid-sealed relation with the flexible hydraulic conduits 20 or 21 leading to the receivers 18 and 19 of each gun G, respectively.

As clearly shown in Fig. 6, each receiver comprises a tubular member 54 formed at one end 55 to receive the flexible hydraulic conduit 20 or 21, as the case may be. A piston 56 is mounted within the tubular member 54 with one end portion 57 projecting without the tubular member and provided at its inner end with an obturator cup 58. To ensure movement of the piston axially of the tubular member 54, a packing and guide gland 59 is secured to the tubular member about the piston 56 as shown. Rotatably mounted clips 60 and 61 are secured to the piston and tubular member, respectively, and a cord or chain 62 is secured to the clip 60 and trained through an eyelet on the clip 61 where it is secured to a weight 63 normally acting to retract the piston 56. A horizontal deflection receiver 19 and vertical deflection receiver 18 is mounted upon each gun or gun cradle, as desired, to actuate the sights thereof in accordance with transmitted lateral and vertical deflections, or the outer ends of the pistons 56 of the receivers may be formed to serve as the sights directly.

In the embodiment shown, the receiver 19 is mounted so that the piston 56 will serve as the front sight movable in lateral deflection and the receiver 18 is so mounted that the piston 56 thereof will serve as the rear sight movable in vertical deflection.

In operation, the conduits 14 and 17 are connected with the transmitters 11, 12, 13 and 15, 16

and cylinder blocks 36, 38 through the cylinders 51, respectively. Also the conduits 20 leading from the bores 39 of vertical deflection cylinder block 36 are connected to the vertical deflection receivers 18 and the conduits 21 leading from the bores 39 of lateral deflection cylinder block 38 are connected to the lateral deflection receivers 19 of each gun. The system is then filled with a suitable fluid and the pistons 56 of the receivers 18 and 19 are adjusted to define a line of sight in the vertical plane containing the axis of the bore when the various transmitters are at zero reading which will be with the pointers 29 thereof disposed centrally of the scales S. The adjustment may be effected by the adjusting screws 41 and plugs 40. It will, of course, be understood by those skilled in the art that the sights, either formed by the pistons 56 or controlled thereby, may be initially displaced with respect to the axes of the bores of the guns to effect calibration of the battery. The superelevation, vertical deflection, lateral deflection and arbitrary correction transmitter operators will rotate the handwheels 28 of their respective transmitters to position the pointers 29 thereof in accordance with the deflections to be transmitted. Displacement of the ends of the screws 24 from their normal zero central positions within the transmitter cylinders will displace the fluid within conduits 14, 17 and the pistons within the cylinders 51, piston rods 52 and cylinder blocks 36, 38 accordingly in proportion to the additive displacements effected by the transmitters connected thereto. Movement of the deflection cylinder blocks relative to the pistons 43 will displace the fluid in the bores 39 and conduits 20, 21 to likewise displace the pistons 56 in accordance with the transmitted deflections and thereby set the sights in conformity with the transmitted deflections.

The cam 45 is designed so that in its normal position the pistons 43 and piston rods 44 will occupy such positions that the sights on the guns when trained upon a target will cause all guns to be directed at the same point; that is, the point fixed by the transmitted deflections and usually calculated by a suitable predictor such as the predictor P in my copending application, Serial No.387,657 filed April 9, 1941. To cause each of the guns to systematically search about the point fixed by the transmitted deflections, the lever 47 is moved to the left as shown in Fig. 4 which displaces the cam 45 to the left and which is designed to effect such relative movement of the piston rods 44 and pistons 43 as to cause the sights to be displaced in a manner such that number 1 gun will search up and to the right, number 2 gun will search up only, number 3 gun will search up and to the left, and number 4 gun will search left only. Upon returning the lever 47 to its normal initial position the sights will also return to their originally deflected positions. To cause the guns to search in directions opposite to those above specified, the lever 47 and cam 45 will be displaced to the right as viewed in Fig. 4. The area to be searched may be controlled by the amount of displacement of the cam 45.

As will be clearly seen from Fig. 6, the weight 63 of each receiver will serve to urge the piston 56 thereof toward a normal retracted position adjacent the input end of the flexible cable 20 or 21, thus creating a back pressure upon the fluid in the conduits and tending to restore the entire system to its original position of zero displacement.

Having now described a present preferred embodiment of the invention, I claim:

1. In a hydraulic transmission system in combination, a vertical deflection receiver having a piston and a piston rod adapted to serve as a sight, a lateral deflection receiver having a piston and a piston rod adapted to serve as a sight, means for mounting the lateral deflection receiver upon a gun with said piston rod disposed for horizontal movement and to serve as a sight, means for mounting the vertical deflection receiver upon said gun with said piston rod thereof disposed for vertical movement and to serve as a sight for coaction with the lateral deflection sight, and conduits connected to the receivers adapted to transmit fluid from a remote point to said receivers effective to displace said pistons.
2. In a hydraulic transmission system in combination, a frame, a pair of cylinder blocks provided with a plurality of parallel bores, means slidably mounting the cylinder blocks in opposed portions of said frame with said bores in opposed parallel relation, a piston mounted in each of said bores for reciprocable movement to and from adjacent end portions of opposed bores, piston rods secured to said pistons and terminating in spaced relation intermediate the cylinder blocks, a cam mounted on said frame engaging the adjacent ends of said piston rods, means for reciprocating said cam transversely of the piston rods, outlet members for each of said bores secured to the cylinder blocks, a receiver for each bore, each of said receivers having a displaceable piston, conduits connecting each outlet member with its corresponding receiver effective to transmit fluid from the bores to said receivers for displacing the pistons in the latter, and means for sliding the cylinder blocks in said frame.
3. In a hydraulic transmission system, a transmitter comprising in combination a cylinder, a screw having one end portion thereof disposed within the cylinder mounted in interthreaded engagement with an end portion of the cylinder, a handwheel secured to the outer end portion of the screw, a packing cup secured to the end portion of the screw disposed in said cylinder, a pointer slidably mounted upon the cylinder, means biasing said pointer into engagement with said handwheel, a scale mounted upon the cylinder for cooperation with the pointer, and means for securing a conduit to the cylinder.

DOUGLAS E. MORRISON.
